J. A. MARTIN,
CAR ROOF GUARD RAIL.
APPLICATION FILED AUG. 30, 1920.

1,364,843.

Patented Jan. 4, 1921.

UNITED STATES PATENT OFFICE.

JAMES AUTHUR MARTIN, OF JERSEY CITY, NEW JERSEY.

CAR-ROOF GUARD-RAIL.

1,364,843.

Specification of Letters Patent.

Patented Jan. 4, 1921.

Application filed August 30, 1920. Serial No. 406,775.

To all whom it may concern:

Be it known that I, JAMES A. MARTIN, a citizen of the United States, residing in Jersey City, in the county of Hudson and State 5 of New Jersey, have invented certain new and useful Improvements in Car-Roof Guard-Rails, of which the following is a specification.

This invention has as its main object to 10 provide a safety guard rail upon the roofs of freight cars of the roofed or box type, whereby persons whose business necessitates walking over them, are prevented from inadvertently falling to the ground and sustaining 15 consequent injury.

A further object is to provide such devices in forms which may be easily and securely applied to existing cars in an inexpensive manner.

20 Another object is to arrange the guard rails in a continuous manner, not only at the sides and ends of the car, but to extend across to adjacent cars, completely protecting the passage of a person from one car to another.

25 These and other similar objects are attained by the novel construction and arrangement of parts hereinafter described and shown in the accompanying drawing, forming a material part of this disclosure, 30 and in which:—

Figure 1 is a perspective view of a conventional type of roofed freight car, including its usual appurtenances, and showing the application of the invention.

35 Fig. 2 is an enlarged fragmentary side elevational view of the railing, partially in section.

Fig. 3 is a transverse sectional view taken on line 3—3 of Fig. 2.

40 Fig. 4 is a side view showing a modified manner of securing the post on the roof.

Fig. 5 is a front view of the same.

Referring to the drawings in detail, the 45 numeral 10 designates the body of the car, mounted upon trucks 11 resting upon a railroad track, and provided with doors 12, ladders 14, couplers 15, braking means 16, roof 17 and a running-board 18 as usual.

The running-board 18 is fixed centrally on 50 the roof and extends from end to end of the car, providing a level footway for the brakeman or other attendants to pass in the performance of their occupation.

Due to shocks, jars and jolts caused by 55 sudden stops and starts of the car, as usually encountered in operation, the foot-hold upon

the relatively narrow running-board is precarious and often aggravated by weather conditions to the extent that accidents frequently occur, causing dislodgment of the attendant, who, in many cases, is thrown violently to the ground, being hurt, maimed or even killed outright.

In order to avoid such occurrences and fulfil the purposes of the invention, a substantial railing 20, is firmly secured at a suitable height by posts 21 to the roof 17, near its side edges and carried along the ends, as at 22, except at the running-board, where the passage is open.

70 These posts are formed at their upper ends with the usual enlarged heads 23 in which the rails are secured.

While the lower ends of the posts may be shaped and secured to the roof in any desired and substantial manner, in order to avoid perforating the roof for screws or like fastening means, it is preferred to form each of them as a clevis 24 its upper element resting upon the roof at its edge, which is in 80 contact with the bow of the clevis, its lower element passing below the overhanging roof edge and firmly secured to it by the clamp screw 25, as best shown in Figs. 2 and 3.

75 This arrangement readily permits removal or replacement of the railing, as does also the device shown in Figs. 4 and 5, in which the posts are provided with bases 28 resting on the roof and projections 29 on their sides in which mounted on pins 30 are 90 pairs of levers 31, connected by links 32 with clevises 33, their upper elements 34 containing pins 35 used to attach the links 32 and also as guides in slots 36 formed in the posts near their lower ends.

95 The lower elements 37 of the clevises extend under the overhanging roof and are provided with spurs 38 in contact with it and which upon operating the levers 31 are forced in, forming a secure clamping means, 100 the levers 31 being held when raised by pins 39 passing through the posts.

In order to protect a person passing from one car to another coupled thereto the inner end posts have secured rigidly to them, in 105 addition to the rail 22, other rails 22', the same extending parallel and beyond the running board 18 to such length as to nearly meet similar rails extending toward them from the adjacent car.

110 At the top of the steps or ladder 14, the rail section 40 is reduced in diameter and

adapted to slide telescopically within the next section 20, as shown in Figs. 2 and 3.

A tension or pull spring 41 is inclosed in the tubular section, one end being fixed in an eye at the inner end of the section 40, its other end being similarly secured to an eye fixed in a block 42 in the tubular section so as to retract the sliding section when the pivoted latch 43 is raised by manual operation thus leaving a clear passage for an attendant to enter upon or leave the roof without passing over the railing, the slideable section having a hand grip 44 by which it may be operated.

15 This sliding section is further provided with a key 45 movable in a slot 46 formed longitudinally in the tubular section as will be seen in Figs. 2 and 3.

From the foregoing it will be seen that a 20 safety guard railing of a novel and practical nature has been disclosed capable of fulfilling the objects specified.

Having thus described my invention, what I claim as new and desire to secure by 25 Letters Patent, is:—

1. The combination with a car roof having a central longitudinal foot-way, of safety guard rails disposed on said roof adjacent its side and end edges except at said 30 footway, telescopic sections at the ends of the side rails, posts for said rails, and means for removably engaging said posts directly to the overhanging edges of the roof.

2. The combination with a car compris-

ing a body, a roof, a running-board on the 35 roof and a ladder on the body leading to the roof, of a railing inclosing said roof except at the ends of the running-board, a movable section in said railing, means for normally locking said section, and means 40 for retracting said section permitting access from the ladder to said roof.

3. The combination with a car having a 45 roof and foot-way thereon, of guard rails inclosing said roof except at the ends of said foot-way, posts for supporting said rails, offset clamp clevises formed at the bottoms of said posts adapted to engage over the marginal edges of said roof, and rigid bars extending in parallel from the 50 end posts in register with said foot-way to approximately half the distance to adjacent cars when coupled thereto and permitting passage therebetween.

4. The combination with a car having a 55 roof and foot-way thereon, of guard rails inclosing said roof except at the ends of said foot-way, posts for supporting said rails, bases on the bottoms of said posts, clamp elements slidably engaged on the posts, said 60 elements having a part engageable below the roof, and levers for forcing said elements against the lower side of the roof below said bases.

In testimony whereof I have signed my 65 name to this application.

JAMES AUTHUR MARTIN.
